US00D786275S

(12) **United States Design Patent** (10) Patent No.: **US D786,275 S**
Yuk (45) Date of Patent: ** *May 9, 2017

(54) **DISPLAY SCREEN OR PORTION THEREOF WITH GRAPHICAL USER INTERFACE**

(71) Applicant: **Samsung Electronics Co., Ltd.**, Suwon-si, Gyeonggi-do (KR)

(72) Inventor: **Seungju Yuk**, Seoul (KR)

(73) Assignee: **SAMSUNG ELECTRONICS CO., LTD.**, Gyeonggi-Do (KR)

(*) Notice: This patent is subject to a terminal disclaimer.

(**) Term: **15 Years**

(21) Appl. No.: **29/560,826**

(22) Filed: **Apr. 11, 2016**

Related U.S. Application Data

(63) Continuation of application No. 29/495,722, filed on Jul. 3, 2014.

(30) **Foreign Application Priority Data**

Jan. 3, 2014 (KR) 30-2014-0000467

(51) **LOC (10) Cl.** **14-14**

(52) **U.S. Cl.**

USPC **D14/485**

(58) **Field of Classification Search**

USPC D14/485-495; D16/134, 200, 219
CPC . G06F 3/0482; G06F 3/04817; H04N 1/4223;
H04N 7/181

CLAIM

I claim, the ornamental design for a display screen or portion thereof with graphical user interface, as shown and described.

DESCRIPTION

FIGURE is a front view of a display screen or portion thereof with graphical user interface showing my new design.

The broken lines are for environmental purposes only and form no part of the claimed design.

1 Claim, 1 Drawing Sheet
